UNITED STATES PATENT OFFICE.

HOWARD J. MURPHY, OF READING, MASSACHUSETTS, ASSIGNOR, BY MESNE ASSIGNMENTS, TO THE BASSICK MANUFACTURING COMPANY, OF CHICAGO, ILLINOIS, A CORPORATION OF DELAWARE.

LUBRICATING SYSTEM AND APPARATUS.

Application filed March 14, 1922. Serial No. 543,647.

This invention pertains to improvements in lubricating systems and apparatus, and more particularly to that class of lubricating apparatus wherein lubricant may be delivered under pressure to the part to be lubricated.

It is among the objects of the invention to provide lubricating apparatus wherein a lubricant-receiving part located in a relatively inaccessible place may be conveniently reached and coupled to a lubricant-expelling device.

In the drawings which show preferred embodiments of my invention:—

Fig. 1 is a side elevation of the discharge end of a lubricant-expelling device coupled to a lubricant-receiving part;

Fig. 2 is a view similar to Fig. 1, except that it is partly in section in a central vertical plane;

Fig. 3 illustrates a modification of my invention;

Fig. 4 is a view similar to Fig. 3, being partly in section in a central vertical plane; and

Fig. 5 illustrates another modification of my invention.

Referring to the drawings and to the preferred form of my invention illustrated in Figs. 1 and 2, I have provided a lubricant-expelling device typified by the barrel 6 of a grease gun, which may resemble that shown in my co-pending application Serial No. 543,643, filed herewith. Cooperating with the lubricant-expelling device, I have provided a discharge conduit adjustable to various angles relative to the expelling device and provided at its discharge end with a coupling 7, preferably valved as shown, which may be like that shown in my co-pending application above referred to, being as illustrated engaged with a lubricant-receiving nipple 8 similar to the one shown in said co-pending application.

The preferred form of conduit connecting the barrel 6 and coupling or nozzle 7 includes two angles, the outer end being mounted for swinging movement relative to the inner end thereof so that, by swinging movement about the coupling, various angles between the axis of the lubricant-expelling device and the axis of the coupling may be provided, the axis of the coupling preferably being as illustrated somewhat off-

set from the axis of the barrel of the lubricant-expelling device, but preferably, as illustrated, in substantial parallelism therewith.

The preferred form of conduit illustrated in Figs. 1 and 2 includes an elbow 9 secured to the discharge head 10 of the grease gun by being threaded into the tubular portion 11 projecting from said head. The elbow 9 is adapted to deliver lubricant to an elbow 12 swiveled relative thereto, and, to provide a tight joint while permitting this relative swinging or swiveling movement, I have provided a tubular connection 13 between said elbows rigidly secured by threads to the elbow 12 and secured to the elbow 9 by an enlarged portion 14 adapted to form a tight joint by being pressed against a suitable seat by the pressure of the lubricant in the conduit. The seat for the projection 14 may be and preferably is, as illustrated, provided by a bushing 15 screwed into the elbow 9.

The nozzle or coupling 7 and valve cooperating therewith is fully described in my said co-pending application and need not be described in detail herein. The connection thereof with the elbow 12 is preferably, as illustrated, such as to permit turning of the nozzle for the coupling operation without correspondingly turning or swinging the barrel 6 of the grease gun, and to this end I have connected the nozzle 7 to the elbow 12 by a tubular part 16 resembling somewhat the tubular part 13, but preferably facing in the opposite direction to permit rigid connection between the tubular part 16 and the elbow 12 by threads, while permitting turning movement of the nozzle.

The thread form of connection illustrated includes the bushing 17 providing a seat for the enlarged head 18 of the tubular part 16 and threaded to permit connection thereof with the nozzle 7 by the interiorly threaded sleeve 20, so that pressure in the nozzle of the gun tends to maintain a joint tight against leakage of lubricant between the tubular part 16 and the parts associated with the nozzle.

In Figs. 3 and 4, I have shown a connection permitting use at various angles relative to the nipple of a lubricant gun having a discharge nozzle rigidly secured to the barrel of the gun. The preferred form of connection illustrated includes a separate angled

connection provided at one end with a grease-receiving nipple 30 adapted to be coupled to the nozzle 31 of the gun and provided at its other end with a coupling 32, 5 preferably valved as illustrated and adapted to engage a lubricant-receiving nipple 33 on the part to be lubricated. By initially applying the angled connection to the part to be lubricated so that the nipple 30 faces 10 in a convenient angle, the necessity for an angled nipple is obviated and the barrel of the gun need not be swung transversely to its axis during the coupling operation. In places where such swinging is practicable, 15 the angled connection may be initially applied to the gun and then connected to the nipple 33.

In Fig. 5 I have shown the use of a flexible hose 40 provided at one end with a grease-receiving nipple 41 and at the other with a coupling of the type illustrated in the other figures, the outside portion thereof mounted 20 to turn without corresponding turning movement of the flexible hose.

25 While I have shown and described preferred embodiments of my invention, it will be understood that changes involving omission, substitution, alteration and reversal of parts, and even changes in the mode of operation, may be made without departing 30 from the scope of my invention, which is best defined in the following claims.

Claims:

35 1. A lubricating device comprising, in combination, a source of lubricant under pressure communicating with a discharge conduit, a valved coupling at the discharge end of said conduit, said coupling presenting a part located within said coupling for 40 turning movement relative to the remainder of said coupling, to effect quick engagement and disengagement of said nozzle with a lubricant-receiving part and for effecting open-

ing and closure of the valve in said valved coupling, and a swivel joint intermediate 45 the ends of said conduit permitting swinging of said nozzle and of the source of lubricant relative to each other to facilitate engagement and disengagement with the lubricant-receiving part. 50

2. Lubricating apparatus comprising, in combination, a lubricant-expelling device having a discharge conduit, said conduit including a swivelled joint providing a transverse pivot having an enlarged portion 55 pressed against a cooperating seat by the pressure of the lubricant in said conduit, and a valved coupling beyond said joint, said coupling turnable relative to said joint for effecting cooperative engagement with a lubricant-receiving nipple. 60

3. Lubricating apparatus including a lubricant supply barrel, a valved coupling having its axis offset from the axis of said barrel, a conduit connecting said barrel and said coupling and a double swivel joint between the barrel and the coupling for permitting said barrel to rotate about and swing relative to the axis of said coupling when said coupling is engaged with a lubricant-receiving 70 nipple. 75

4. Lubricating apparatus including a lubricant supply barrel, a valved coupling having its axis permanently offset from the axis of said barrel, said coupling being connected 80 to a lubricant receiving fitting by rotation about its own axis, a conduit connecting said barrel and said coupling, and swivel joint means between the barrel and the coupling permitting rotation of said coupling alone 85 about its own axis, and substantially universal movement of said barrel with respect to said coupling.

In testimony whereof, I have signed my name to this specification.

HOWARD J. MURPHY.
